C. L. STOKES,
LIQUID FEED SYSTEM.
APPLICATION FILED NOV. 29, 1916.

1,319,913.

Patented Oct. 28, 1919.

UNITED STATES PATENT OFFICE.

CHARLES L. STOKES, OF LOS ANGELES, CALIFORNIA.

LIQUID-FEED SYSTEM.

1,319,913.

Specification of Letters Patent. Patented Oct. 28, 1919.

Application filed November 29, 1916. Serial No. 134,137.

To all whom it may concern:

Be it known that I, CHARLES L. STOKES, a citizen of the United States, residing at Los Angeles, in the county of Los Angeles, 5 State of California, have invented new and useful Improvements in Liquid-Fee Systems, of which the following is a specification.

This invention relates to systems for feeding or lifting liquids, and, in its more particular phase, hereinafter described, relates to systems for feeding or lifting liquid fuel for internal combustion engines of any type.

This invention has particularly to do with 15 improvements upon the system shown and described in my applications S. Nos. 91,303; 120,069 and 124,473; filed April 15, 1916, September 14, 1916, and October 9, 1916, respectively; and this invention has for an 20 object the provision of means for increasing the efficiency of lifting the liquid fuel, both under normal conditions and under extraordinary conditions, as when an automobile is ascending or descending a steep grade.

25 In systems of the character herein described, and described in my co-pending applications, it will be noted that the service reservoir, to which the liquid fuel is lifted by suction, is in permanent communication 30 with the atmosphere; that is, communication with the atmosphere is never cut off by any positive means. I make this atmospheric communication in such a manner as to not only supply atmospheric pressure to 35 the surface of the liquid in the service reservoir during the periods when suction is not being applied; but also to apply air to the column of fuel being lifted. So that, when the fuel is being lifted into the service 40 reservoir, the air from atmosphere passes into the reservoir mixed with the fuel being raised. It is a particular object of this present invention to provide improved means for admitting said air in such a manner as to 45 increase the efficiency of the lifting operation; while, at the same time, of course, the air inlet performs its other function, as hereinafter described. These objects, and other objects which will hereinafter appear, are 50 accomplished by means of my device, of which the following described form is typical.

I refer to the accompanying drawings in which: Figure 1 is a diagram showing the 55 various operative parts of my system, and showing their relations and connections;

Fig. 2 is an enlarged detail section of the connection to the main fuel tank; Fig. 3 is an enlarged detailed section showing the means of admitting atmosphere to the lifting line and to the service reservoir; Fig. 4 is an enlarged detail section of the service reservoir; and Fig. 5 is an enlarged detail section showing a modified structure in which the service reservoir and carburetor 60 are combined as a unit.

In the drawings the fuel tank is shown at 10 at a level lower than the carburetor 11 fed by the liquid from the tank. This tank has the usual filling plug at 12 with an air 70 inlet to apply atmospheric pressure to the liquid in the tank. The lifting pipe 13 connects into a fitting 14 which has a liquid passage 15 communicating with the tank and has also an air nozzle 16 controlled by a 75 needle valve 17 to admit air into liquid flowing from the tank into pipe 13. The air is drawn through the pipe 18, whose upper end is above the liquid level in tank 10. The amount of air admitted at nozzle 16 may be 80 regulated or completely shut off by valve 17.

The lifting pipe 13 is provided in its vertical portion with an interior air tube 20. This air tube is open at its upper end at 21 to atmosphere and may be provided with an 85 upwardly closing check valve 22 operated by a float 23 to close off communication to atmosphere in case the tank 10 should rise very high. This valve, however, is an emergency means. Normally, the upper end 90 of tube 20 is above the liquid level in tank 10 so that no liquid can flow out. In fact, the uppermost perforation 24 in the air tube (which is on or about the level denoted 24^a in Fig. 1) is above any ordinary level of 95 fuel in tank 10, while, at the same time, it is below the ordinary level of the fuel in the service reservoir 25. This air tube 20 is preferably of small dimensions. For instance, while lifting tube 13 may be $\frac{1}{4}$ " in. 100 side diameter, the air tube will probably be only about $\frac{1}{16}$ " inside diameter and the perforations 24 are of about the size made by a No. 64 drill. The lower end of tube 20 may either be closed, or a similar hole made at its 105 lower end. It will be seen that although the uppermost hole 24 is normally above the liquid level, certain of the holes 24 are below the liquid level. It is only necessary for the operation of my system, that the uppermost 110 hole 24 be above the liquid level; but this does not mean that all the other holes must

be below the normal level of liquid in tank 10.

The pipe 13 leads to the top of the service reservoir 25 and discharges into that reservoir through the cover 30 and through a nipple or baffle 31 and strainer 31^a extending into the reservoir beneath the cover; this baffle being for the purpose of preventing the mixed air and liquid being drawn immediately to the suction port 32 before the air and liquid can separate. The suction pipe 33 extends from the intake manifold 34 of the engine (at a point above the throttle valve 35) to the suction port 32 of service reservoir 25. A valve 36 is adapted to close the port 32 by upward movement; and this valve is loosely mounted upon a lever 37 pivoted at 38 to a wall of the service reservoir and connecting at its end with float 39. This float is preferably somewhat weighted (as compared with the weight of ordinary floats of this character) so that its weight is sufficient to pull the valve 36 down against the suction tending to keep it up, when the liquid level in reservoir 25 has fallen so that the liquid support of the float it partially withdrawn. From the lower part of the reservoir 25 the liquid fuel passes out through pipe 40 to the carbureter 11, passing the upwardly closing check valve 41, provided for the purpose of keeping the fuel in the carbureter from being sucked back into the reservoir 25 when suction is applied to the reservoir. The valve 41 may be placed at the carbureter and seated by gravity.

When the service reservoir is full of liquid the float 39 moves up to the position shown and moves the valve 36 to close suction port 32. The closure of this suction port prevents further application of suction to the reservoir. The gradual flow of liquid out of the reservoir to the carbureter lowers the liquid level in the reservoir and takes away the liquid support of float 39. When the liquid level has fallen to such an extent that the unsupported weight of the float is sufficient to overcome the suction tending to support valve 36, then the float will fall, carrying valve 36 with it and suction will be reapplied to the upper part of the reservoir. In an actual apparatus the arrangement is made such that the liquid level in the reservoir falls by about one quarter of an inch before the valve 36 is moved downwardly.

Suction being applied to the reservoir is, of course, also applied to pipe 13. The liquid from tank 10 normally stands up to a height depending upon the amount of liquid in the tank; but the uppermost air port 24 is always higher than the normal liquid level. Suction applied to pipe 13 will immediately begin to draw air through all the air ports 24 that are uncovered; but the amount of air introduced through these

ports is insufficient to break the suction. The fuel, therefore, begins to rise in pipe 13 and, after passing any port 24, this fuel is intermingled with the air drawn through the port. The valve 17, at the lower end of pipe 13, may be regulated to also admit a restricted quantity of air, or this lower admission of air may be entirely cut off; so that the fluid rising to the ports 24 may either be mixed liquid and gas or pure liquid. In any case, a certain amount of air is introduced at the ports 24, and the column of mixed liquid and air is then drawn up through the pipe 13 and over into the reservoir 25, where the liquid and air separate, the air being drawn into the engine manifold and the liquid settling into the body of liquid in the reservoir. As the liquid level in the reservoir rises, the float 39 is moved upwardly until the valve 36 is again seated, cutting off the application of suction. Immediately the application of suction is cut off, the column of mixed liquid and air in pipe 13 is arrested in motion and the liquid settles back through the pipe to its normal level. By this action one or more of the ports 24 are again uncovered and communication with atmosphere is restored to the reservoir 25 through the pipes 13 and 20.

Now the peculiar function of the plurality of air ports 24 is this: to provide for feed of air into the column of liquid at a point or points lower down in the lifting pipe 13 than would be provided by a single port (which must be above the highest normal liquid level); and to provide for stages in the column of mixed liquid and air, the column being lighter in the upper stages. This not only provides for efficiency in lifting the liquid—enabling me to lift a long column with a low vacuum—but also provides for introduction of air into the column of liquid when for any reason the liquid level is low; as when the liquid is low in tank 10, or as when the automobile is moving up a steep grade. With these provisions my system is particularly effective; raising fuel a great distance with a comparatively small vacuum; and therefore raising it constantly and uniformly (though intermittently) in spite of variations in the engine suction.

It will now be seen that the air ports 24, located at a point above the normal level of liquid, perform two functions; one to admit atmospheric pressure to the liquid in the service reservoir when suction is not being applied and when the atmospheric pressure is needed to allow the liquid in the service reservoir to flow out; and the other being to supply air in stages, at different points, to the rising column of liquid in pipe 13 to facilitate the upward movement of the column. So far as either function of ports 24 is concerned, it is more or less immaterial

whether air is admitted at the lower end of pipe 13; although the admission of some air at the lower end of the pipe may facilitate somewhat the raising of the mixed column 5 of air and liquid—depending upon the position of the lowermost port 24. The points at which ports 24 make communication depend more or less on the vertical distance through which the liquid is lifted, the variations 10 in this distance due to the causes stated, the amount of suction available, etc.

In Fig. 5 I show the service reservoir 25^a constructed in a unit with the carbureter 11^a. The service reservoir has the same float 39 15 operating the valve 36 through the medium of the lever 37 connected with the float. The suction pipe 33 connects in the same manner as before described with the intake manifold 34 of the engine above the throttle valve 35. The carbureter itself may be of any of 20 the usual constructions; embodying for instance the liquid nozzle 50 controlled by needle valve 51 and located in the air passage 52 which connects directly with the intake 25 manifold of the engine.

Liquid fuel is supplied to the nozzle 50 from the fuel chamber 53, which is in communication at 62 with atmosphere. This chamber has no float or valve as is ordinarily 30 the case; but may have a float 60 which moves a valve 61 to close an air port 62 when, for any reason, the chamber may be flooded. A horizontal liquid passage 55 may connect the bottom of reservoir 25^a 35 with the bottom of chamber 53; and any suitable check valve, indicated at 56, may be placed in this communication to prevent back flow of liquid from chamber 53 to reservoir 25^a when suction is applied to the reservoir 25^a. Whenever the liquid level in reservoir 25^a is higher than that in chamber 53, liquid will flow from the reservoir to the chamber to replenish the supply in the chamber. The maximum height of liquid in chamber 53 is level with the maximum height in reservoir 25^a; and this maximum height is controlled entirely by the action of float 39 and valve 36; because whenever the valve 36 is closed, it is impossible to introduce liquid into the reservoir by the suction action.

In this last explained form of system, it will be seen that the float 39 not only acts to maintain the level of liquid in the chamber 25^a but also acts to maintain the level of liquid in chamber 53 and to limit the rise of liquid in that chamber. Consequently, the float 39 performs a double function in that it controls the application of suction 60 to the service reservoir and controls the lifting of liquid from tank 10 and the filling of the reservoir, and also controls the liquid level in the chamber 53 which directly and immediately feeds the carbureter proper, 65 particularly in case where the level of the

carbureter may be below that of the fuel in tank 10.

As hereinbefore stated, the principal improvement herein concerned is in the manner of introducing the air to the lifting column. And to this improvement I direct the following claims; but these claims are not necessarily limited to the specific structure herein described, as variations and modifications may be made without departing 70 from my invention. For instance, the exact means of introducing air may be varied. It will be noted that I explain the introduction of air at 16 at the lower end of the lifting pipe and then explain a different means for 80 introducing air into the lifting pipe above its lower end; but, for all intents and purposes, the admission at 16 is, or may be, substantially the same as admission through the ports 24; so that the port 16 is included 85 within the broad statement of an air admission means below the normal level of liquid in the lifting pipe.

Having described a preferred form of my device, I claim:

1. In a liquid feed system, the combination of a liquid tank of considerable depth, a liquid reservoir above the tank, a communication between the tank and the reservoir extending to and adapted to draw liquid 95 from said tank throughout a wide range of variation of level of the liquid therein; means to apply suction to the upper part of the reservoir, and means to restrictedly admit atmosphere to said communication simultaneously at vertically spaced points at least one of which is above the liquid level in the tank and others of which are at substantially different depths below said level.

2. In a liquid feed system, the combination of a liquid tank, a liquid reservoir above the tank, a communication between the tank and the upper part of the reservoir, means for applying suction to the reservoir, means for discontinuing said suction, and means for restrictedly admitting air to said communication simultaneously at vertically spaced points below the liquid level in the reservoir and at least one of said points being above the liquid level in the liquid tank.

3. In a liquid feed system, the combination of a liquid tank, a liquid reservoir above the tank, a communication between the tank and the reservoir, means for applying suction to the upper part of the reservoir, valve means in the reservoir for cutting off suction to the reservoir, a float for actuating said valve means, and means for restrictedly admitting air to said communication simultaneously at vertically spaced 120 points below the liquid level in the reservoir and at least one of said points being above the liquid level in the liquid tank.

4. In a liquid feed system, the combination of a liquid tank, a liquid reservoir 130

above the tank, a communication between the tank and the reservoir, means for applying suction to the upper part of the reservoir, means for discontinuing said suction, 5 means for restrictedly admitting air to said communication simultaneously at vertically spaced points below the liquid level in the reservoir and at least one of said points being above the liquid level in the liquid tank, 10 and means for restrictedly admitting atmosphere at the lower end of said communication near the liquid tank.

5. In a liquid feed system, the combination of a liquid tank and a liquid reservoir 15 above the tank, a communication between the tank and the reservoir, means for applying suction to the upper part of the reservoir, valve means in the reservoir for cutting off suction to the reservoir, a float for 20 actuating said valve means, means for restrictedly admitting air to said communication simultaneously at vertically spaced points below the liquid level in the reservoir and at least one of said points being above 25 the liquid level in the liquid tank, and means for restrictedly admitting atmosphere at the lower end of said communication near the liquid tank.

6. In combination with a carbureter having a fuel chamber open to atmosphere, a 30 low level liquid fuel tank and a high level service reservoir feeding the carbureter chamber by gravity, a communication between the tank and reservoir, means to apply 35 suction to the reservoir, and means to restrictedly admit atmosphere to said communication simultaneously at vertically spaced points one of which is above the liquid level in the communication and others 40 of which are below said liquid level.

7. In combination with a carbureter, a 45 low level liquid fuel tank, a liquid fuel reservoir above the carbureter and in communication therewith to supply it with fuel, a communication between the tank and reservoir, means for restrictedly admitting atmosphere to said communication simultaneously at spaced points one of which is above the liquid level in the communication 50 and others of which are below said liquid level, and means to apply to the upper part

of the reservoir the same suction that is applied to the carbureter to maintain a partial vacuum in the reservoir and to draw therefrom the air which enters it with the fuel. 55

8. In combination with a carbureter having a liquid fuel chamber open to atmosphere, a low level liquid fuel tank, a high level service reservoir feeding the carbureter chamber by gravity, a communication between 60 the tank and reservoir, means to restrictedly admit atmosphere to said communication simultaneously at points one of which is above the liquid level in the communication and others are below said liquid 65 level, and means to intermittently apply to the upper part of the reservoir the same suction that is applied to the carbureter to maintain a partial vacuum in the reservoir and to draw therefrom the air which enters 70 it with the fuel.

9. In combination, a carbureter, a low level liquid fuel tank, an upper reservoir in communication with said low level tank and feeding the carbureter by gravity, means for 75 applying suction to the reservoir, and means for admitting atmosphere to the communication between the tank and the reservoir, said means comprising an air pipe arranged 80 interiorly of said communication and having one end open to atmosphere.

10. In a liquid feed system for internal combustion engines, the combination of a liquid tank, a liquid reservoir above the tank, a communication between the tank and the reservoir, means for applying suction to the upper part of the reservoir, and means for restrictedly admitting air to said communication between the tank and the reservoir, said means comprising an air pipe arranged 85 interiorly and longitudinally of said communication and having one end open to the atmosphere and having a series of openings along its length through which air may 90 enter said communication. 95

In witness that I claim the foregoing I have hereunto subscribed my name this 27th day of November 1916.

CHARLES L. STOKES.
